United States Patent Office.

GEORGE W. WINTERRINGER, OF FREDERICKTOWN, OHIO.

Letters Patent No. 76,963, dated April 21, 1868.

IMPROVEMENT IN GATES.

The Schedule referred to in these Letters Patent and making part of the same.

Be it known that I, GEORGE W. WINTERRINGER, of Fredericktown, county of Knox, and State of Ohio, have invented a new and useful Improvement in Gates, of which the following is a full, clear, and exact description, reference being had to the accompanying drawings, making a part of this specification, in which—

Figure 1 represents a side elevation,

Figure 2 a vertical cross-section in the line $x x$, fig. 1, and

Figure 3 a plan view.

The object of my invention is to provide an apparatus of cheap, simple, and durable construction, which may be applied to any carriage or large farm-gate, without any material change in its general build, to enable travellers to open and pass through from either side of it, without being obliged to dismount from the horse or carriage to open or close the gate.

In the drawings, A represents an ordinary farm or road-gate, standing between the posts B B. I prefer to mortise the post into a large beam running parallel to and under the gate, the said beam being supported at each end by cross-pieces, lying at right angles to it. This framework, A', may be made of hewn or sawed logs, and, embedded in the earth, will make a solid foundation for the gate to stand upon. It will also enable the removing of the gate easily from place to place, and protect it in position against the working of the frost.

In the centre of the gate is built an upright piece of timber, C, and which extends nearly from the bottom, up through and above the gate, so high that the opening-mechanism will be entirely out of the way of foot-passengers, but low enough for the convenient use of the mounted traveller. This shaft C is slotted, and when passed down over the bars of the gate c c, may be adjusted at any desired height. The object of making the upright shafts C and D slotted, is that the whole frame of the apparatus for opening the gate may be moved forward towards the front post, (of the gate,) as well, also, that it may be raised or lowered at pleasure. By constructing the centre post of the gate farther forward, it might be made of suitable length, and thus the centre shaft, C, which now is additional, could be dispensed with, the box C' resting upon the centre post of the gate. The slotted shafts C D will allow of my invention being applied to farm-gates already in use. The other plan of setting the box C' upon the centre post of the gate could be carried out in making new gates.

Upon a round iron pin, driven into the upper end of this shaft or centre post C, is set the box C', of convenient length, the pin h extending through to the top of the box, over which is placed the cover f. The pin h should have a flattened oblong head, in order that the springs m, which are set in a recess longitudinally with the box C', and held firmly in place by the pins m', may keep the box in its proper position, and the handles G' always at right angles with the gate A. It will be apparent, without the use of the springs m, or their equivalents, that the handles G' would remain in the position at which the hand should be disengaged of the person driving through the gate, and therefore not available to the next one who should wish to open it; but by the action of the springs m, no matter in what direction the handles G' may point at the time the traveller disengages his hand, upon the closing of the gate they will resume a position at right angles with it.

The forked lever of the handles G' G' can be constructed passing through the box, or over it, as represented in the drawings, C². The forked-shaped lever is preferred, on account of its strength, though it may consist only of a straight pole, of sufficient length and size to operate the fastening of the gate.

On each lower end of the box C' are projections F, figs. 1 and 3, of triangular shape, which are bevelled at such an angle that when they come in contact with the bevelled end of the slotted and movable shaft D; which is built upright and parallel to the shaft C, between it and the front post of the gate A, the action of the bevelled projections F upon the inverted triangular surface E of the shaft D will be to raise this shaft, and, consequently the latch a of the gate, which is firmly secured to it by pins d d.

The slotted shaft D is secured in its position, near to its upper end, by the bar b, connecting it to the centre shaft or post C, and at its bottom by the latch a of the gate.

On each side of the shaft D are driven pins d d, into the bars c c of the gate, which allow it only a vertical motion. The latch-board I should be constructed with bevelled angles a², of sufficient length for the latch to

become easily adjusted with reference to the force with which the gate closes itself. This is accomplished by the weight H, attached to the cord connecting it to the plauk K, which extends from the centre shaft or post C, beyond the hind end of the gate A, and as far as is necessary to cover the projection B'.

The operation of my invention is as follows:

The person in the carriage, driving through, drives his horses under the forked lever G', and, rising from his seat, takes hold of the handle, and brings in contact the bevelled surfaces E and F of the box C', and slotted shaft D, fig. 1, by which means the latch a is disengaged, being raised from its socket a' with the vertical movement of the shaft D. Pushing open the gate, he holds on to the lever G' until the hind wheels of the carriage are so far advanced that the gate, in closing, cannot come in contact with them when he lets go the lever. The gate is then closed by the action of the weight H, and the lever G' made to resume a position at right angles with the gate by the action of the springs m upon the square surface of the iron pin h, upon which the box C' revolves, thus allowing the lever G' to be turned round end for end.

What I claim as new, and desire to secure by Letters Patent, is—

1. The combination and arrangement of the bevelled angles E and F of the box C', and slotted shaft D, operated by the forked or straight lever G' substantially as and for the purposes herein described and set forth.
2. In combination with the above, I claim the springs m, or their equivalent, the flattened and oblong head of the bolt h, the operating-lever G', all arranged and operated substantially as and for the purposes herein described and set forth.
3. In combination with the above, I claim the weight H, arranged and operating as described, for the purpose of closing the gate, as specified.

In witness whereof, I hereto subscribe my name in the presence of two attending witnesses, this day of March, 1868.

GEORGE W. WINTERRINGER.
